UNITED STATES PATENT OFFICE.

JAMES SHAW AND WILLIAM H. HARRISON, OF PATERSON, NEW JERSEY, ASSIGNEES
OF ONE-THIRD TO JERE L. WENTZ, OF PASSAIC, NEW JERSEY.

SAFETY-SHUTTLE-CONTROL ATTACHMENT FOR TEXTILE LOOMS.

Application filed August 21, 1922. Serial No. 583,150.

To all whom it may concern:

Be it known that we, JAMES SHAW and WILLIAM H. HARRISON, citizens of the United States, and residents of the city of Paterson, in the county of Passaic and State of New Jersey, have invented certain new and useful Safety-Shuttle-Control Attachments for Textile Looms, of which the following is a specification.

10 Our invention relates to improvements in safety shuttle control attachment for textile looms.

In weaving cloth, the loom is provided with shuttle boxes at each side from which 15 the shuttles carrying the filler threads travel across the loom, and through the warp threads. In the operation of weaving, it becomes necessary from time to time to take out and replace a shuttle and it is necessary 20 that the shuttle so removed, be replaced in its proper box, for the reason that if the shuttle is placed in the wrong box and the loom started up, the shuttle will be driven into the warp threads, thereby damaging the 25 threads and the fabric. The loss resulting from such an error includes not only the damage to the goods but a considerable loss of time.

The object of our invention is to provide means whereby a shuttle will be prevented from being placed in the wrong box. The preferred form of our improved device is illustrated in the accompanying drawings in which—

35 Figure 1 is an end view of a loom provided with our improved device.

Figure 2 is a side view of the same.

Figure 3 is a top view of a shuttle box.

Figure 4 is a side view of the same.

40 Figure 5 is a section on the line 5—5 in Figure 4.

Similar reference characters refer to similar parts throughout the several views.

45 At each side of loom 1, are provided shuttle boxes 2 and 4 respectively. The shuttle travels across the loom to and from these shuttle boxes, the operation of which is understood.

Our invention relates particularly to the 50 construction of the shuttle box and the means for locking or obstructing the same. In the side of the shuttle box 4, is provided a friction plate 5, which is normally pressed into the box 4 by means of a spring 6 and thereby a shuttle 7 entering the box is frictionally engaged and held therein until

driven out across the loom in the usual well known manner.

We provide at the side of the shuttle box, a swinging arm 8 preferably mounted on a pin 9 and normally held out of contact with the friction plate 5 by means of a spring 10 or the like, but adapted to be swung into contact with the friction plate 5 to press it into the box 4 to a position which will prevent 65 the shuttle 7 from entering the box. When in its normal vertical position, as illustrated in Figure 5 the swinging arm 8 does not contact with the friction plate 5, which then operates in the usual manner. When, however the shuttle 7 leaves its box 4, the arm 8 will as hereinafter explained, swing over and press against the friction plate 5 depressing it into the box 4 and thereby obstruct the same until, in the usual operation, 70 the shuttle should be received by the box and thus each shuttle box is obstructed at all times except when it should be entered by the shuttle, as herein explained. Below the arm 8, is provided a cam 11, which is adapted to engage the lower end 8' of the arm 8, whereby the upper end of the arm 8 is forced over against the friction plate 5, pressing it into the shuttle box 4. The cam 11 is operated by means of a connecting rod 12, 75 which forms a connection between the cam 11 and a rocking lever 13 pivotally mounted upon the frame 14 of the loom. This rocking lever 13 is provided with an arm 15, which is connected with the treadle 19 which 80 lies in the plane of travel of the picker arm 16 revolving with the driving shaft 17. As the picker arm 16 revolves in its travel, it will engage and actuate the rocking lever 13, thereby forcing the swinging arm 8 against 85 the friction plate 5 and forcing it into the box 4. We position the arm 15 of the rocking lever 13 so that the box 4 will be obstructed as above described at all times when the shuttle should not be placed there- 90 in, and its operation is synchronized with the movement of the shuttle.

95 Shuttle boxes as above described, are provided at each side of the loom and the devices adapted to close or obstruct the boxes 100 as above described, are connected by means of a connecting rod 18 which causes the respective devices at each side of the loom to operate alternately as above described.

105 It will be understood that each of the shuttle boxes on the loom are equipped with a safety device as above described.

The operation of the device is as follows: The picker arm 16 in its revolution, having struck the treadle 19, will drive the shuttle from its box 4 by means of the arm 20 and as the shuttle leaves the box 4, the arm 15 of the rocking lever will be actuated, and by means of the connecting rod 12, the upper end 8° of the swinging arm 8 will be pressed against the friction plate 5 whereby the shuttle box 4 will be obstructed. The connecting rod 18 will simultaneously swing over the rocking lever 21 on the opposite side of the loom, which will draw down the connecting rod 22 and open the shuttle box 2 to receive the shuttle and this operation will be continued, the shuttle box being obstructed or closed as the shuttle leaves the box and will so remain until the shuttle should be received and the only box open and unobstructed will be that in which the shuttle should be received. It therefore follows that if the operation of the loom is stopped and the shuttle taken out for any purpose, it can be replaced only in its proper box, as the other boxes will be obstructed.

Having thus described our invention, what we claim is:

1. In a device of the character described, a shuttle box, a depressible friction plate therein and means for rigidly holding the friction plate in position to obstruct the

shuttle box immediately after the shuttle is expelled therefrom substantially as shown and described.

2. In a device of the character described, 35 the combination of a loom, a shuttle box thereon, a friction plate in the shuttle box, a swinging arm adapted to contact with the friction plate to press the same into the shuttle box when the shuttle leaves the same, a cam adapted to actuate the swinging arm, a picker arm on the loom and adapted to drive the shuttle and to actuate the cam whereby the swinging arm will be pressed against the friction plate to close the shuttle box immediately after the shuttle leaves the same substantially as shown and described. 40 45

3. In a device of the character described, the combination of a loom, a plurality of 50 shuttle boxes thereon, means whereby a shuttle box is obstructed immediately after a shuttle is discharged therefrom and another shuttle box is opened simultaneously to receive the shuttle so discharged.

4. The combination of a loom of a plurality of shuttle boxes, means adapted to obstruct a shuttle box immediately after a shuttle is discharged therefrom and to simultaneously open a box to receive a shuttle. 55

Signed this 25th day of July, A. D. 1922.

JAMES SHAW.

WILLIAM H. HARRISON.
